UNITED STATES PATENT OFFICE.

JOHN BORGE, OF NEW YORK, N. Y., ASSIGNOR TO BORGE INCINERATOR CORPORATION,
OF NEW YORK, N. Y., A CORPORATION OF NEW YORK.

INCINERATOR.

1,275,653.

Specification of Letters Patent. Patented Aug. 13, 1918.

Application filed April 6, 1916, Serial No. 89,302. Renewed January 11, 1918. Serial No. 211,456.

To all whom it may concern:

Be it known that I, JOHN BORGE, a subject of the King of Norway, and a resident of the city of New York, county of Kings, 5 and State of New York, whose post-office address is Flatiron Building, New York city, have invented a new and useful Improvement in Incinerators, of which the following is a specification.

10 The object of my invention is to provide an apparatus of this class which will efficiently and economically incinerate all garbage or waste material that may be deposited therein. This object is accomplished by 15 my invention, one embodiment of which is hereinafter more particularly set forth.

For a more particular description of my invention, reference is to be had to the accompanying drawings, forming a part here- 20 of, in which—

Figure 1 is a perspective view of my improved incinerator;

Figs. 2, 3 and 4 are sectional views, taken 25 on the lines 2—2, 3—3 and 4—4 respectively of Fig. 5, looking in the direction of the arrows;

Fig. 5 is a longitudinal section of my improved incinerator, the garbage chute, cleaning door, fire box door and ash pit door 30 being omitted, and

Figs. 6 and 7 are sectional views, taken 35 on the lines 6—6 and 7—7 respectively of Fig. 5, looking in the direction of the arrows.

Throughout the various views of the drawings, similar reference characters 40 designate similar parts.

My improved incinerator 1 is provided with a top 2 from which extends a flue 3, 45 sides 4 and a back 5, as well as a front 6, to which front is secured, near its top, a garbage chute 7 normally closed by a hinged lid 8, and below said chute 7 is secured a frame 9 with a cleaning door 10, another 50 frame 11 with a door 12 which permits access to the fire box, and a frame 13 for the ash pit door 14. These three doors are made in the conventional way and hinged to their respective frames in the conventional manner, and each door normally 55 closes a corresponding opening in the front wall 6.

The top 2, sides 4, back 5 and front 6 may be made in any suitable way, but are 60 preferably made out of refractory material,

so that they are capable of withstanding a great deal of heat. These tiles may be put together in any suitable way and covered with asbestos and iron or other insulating or protecting material. 60

The flue 3 of the top 2 runs to a vertically disposed flue which is formed by the inner tiling 15, which tiling is warped at 16 so as to fit the shape of the flue 3 and arched at 17, at its lower edge so as not to interfere 65 with the fire box which is above the grate 19 and between the sides and front and rear walls, and to properly support itself.

The second inner tiling 20 runs parallel to the lower part of the tiling 15 and is 70 mounted in the same way, from the sides 4, and recessed at its lower edge at 21 so as to conform to the shape of the fire box, and at its middle portion it is perforated with an opening 22 to correspond with the cleaning 75 door 10, and at its upper edge it is recessed at 23 so as to permit the vaporized products to escape through the front flue, or these products may escape through the opening 24 in the tiling 15, which opening is opposite the opening 23 and thus get directly up the chimney. It will be noted that the recess 23 is protected from all garbage by a shelf 25 which forms a part of the garbage chute.

A grating composed of bars 26 of refractory or similar material is placed over the fire box and below the level of the cleaning door 10 so as to support all garbage that may be passed through the chute 7. 85

In view of the foregoing, the operation of 90 my improved incinerator will be readily understood. It is used as a garbage receptacle until a sufficient amount of garbage has accumulated and then a fire is built on the grate and the products of combustion 95 escape by the rear flue and thence out through the flue 3 to the chimney to which it is connected. This combustion in the fire box heats the garbage and drives off the volatile products, either through the perforations 24 or the recess 23, and the front flue, and in any event these products are heated and taken from the apparatus and passed up the rear flue along with the products of combustion. 100

While I have shown and described one embodiment of my invention, it is obvious 105 that it is not restricted thereto, but is broad enough to cover all structures that come within the scope of the annexed claim. 110

Having thus described my invention, what I claim is:

A device of the class described comprising a chamber having a top, front, rear and 5 side walls, a pair of vertical interior partitions extending from side wall to side wall within the chamber forming a garbage receiving chamber between them and also forming flues between them and the front 10 and rear walls respectively, a horizontal garbage supporting grate extending between said partitions adjacent their lower ends, a fire grate below the lower ends of said partitions, the front partition having an opening intermediate its ends and a garbage receiving opening leading to the garbage receiving chamber adjacent its upper end, both 15 of said openings being above the garbage

supporting grate, the front wall of the first named chamber having an opening above 20 the upper end of the front partition registering with the garbage receiving opening in the front partition, said front wall also having an opening registering with the opening in the front partition intermediate 25 its ends, said front wall also having a pair of additional openings, one situated above the fire grate and the other below said grate, said top being provided with an outlet flue in communication with the flue adjacent the 30 rear wall, and said rear partition having an opening near its upper end.

Signed at the city, county and State of New York, this 29th day of March, 1916.

JOHN BORGE.
